UNITED STATES PATENT OFFICE.

JOHN H. LESLIE AND JOHN W. LESLIE, OF CHICAGO, ILLINOIS.

SHOW-CASE.

No. 927,060.

Specification of Letters Patent.

Patented July 6, 1909.

Application filed June 13, 1908. Serial No. 438,287.

To all whom it may concern:

Be it known that we, JOHN H. LESLIE and JOHN W. LESLIE, citizens of the United States, residing at Chicago, in the county of Cook and State of Illinois, have invented a certain new and useful Improvement in Show-Cases, of which the following is a specification.

Our invention relates to show-cases, particularly such as are intended to exhibit, while storing, grocery supplies such as rice, sugar, coffee, and the like.

It is illustrated in the accompanying drawings, wherein—

15 Figure 1 is a vertical section through a device containing our invention; Fig. 2, an enlarged detail cross section; Fig. 3, a plan of Fig. 1; Fig. 4, a bottom view; Fig. 5, a bottom view of a detail; Fig. 6, a detail vertical section on line 6—6 of Fig. 1; Fig. 7, a detail section modification; Fig. 8, a vertical section of a modified form of device; Fig. 9, a cross section on line 9—9 of Fig. 8.

Like parts are indicated by the same letter 25 in all the figures.

A is a section open at A¹ and provided with the back A², a bottom A³, a front, preferably of glass, A⁴, a curved connection A⁵ for the bottom and back, and sides A⁶. The front 30 section A⁴ is held in position between the inwardly turned edges A⁶ of the sides and the ribs A⁷ secured to the inside of the sides A⁶.

A⁸ is a transverse rod on which the glass portion A⁴ rests and which also supports the 35 upper end of an inwardly projecting glass portion A⁹.

B B are slotted bars adjustably secured in position on the inside of the side pieces by means of the bolts B¹ B¹. Each of these bars 40 is provided with a lower lip B² to engage the lower end of the glass plate B³ so that the latter may be adjustably secured in position to form an adjustable extension of the glass section A⁹. In the modified form of structure 45 shown in Fig. 7 the glass plate B³ is dispensed with and the lower end of the extension A⁹ is received into sockets A¹⁰ on the inside of the side pieces A⁶ while a corner plate A¹¹ holds the upper end of the part A⁹ and the lower 50 end of the part A⁴ in proper position.

By taking out the upper screw B¹ the bars B can be tilted, whereupon the glasses B³ and A⁹ can both be taken out so as to give access to the interior of the section. Practically 55 the same thing would be accomplished in the

structure shown in Fig. 7 by removing the sockets A¹⁰.

On the side edges of the front portion are two grooves formed, if desired, by turning up the projecting edges C C of the side plates. 60 In these grooves slides vertically the glass door C¹ having the controlling knob C². The grooves are open below so that the door can be inserted and at their upper ends the edge of the sides is forced down as at C³ so as 65 to limit the upper excursion of the door C¹. The door is guided on the inside at its lower part by the ribs C⁴. The bottom A³ is turned up around its outer edge at D so as to form a groove to receive the sides A⁶ and the back 70 A² of the upper section. It is also cut away at its forward end at D¹, being bent so as to form a ledge D² about such opening. At D³ an upwardly projecting indentation or slot is 75 formed in the bottom. The opening D¹ is the filling opening for the lower section and is preferably arranged with relation to the plate A⁹ or its extension B³ so that the angle of repose of the material in the upper section will not cause it to overflow through such 80 opening in the lower section. The lower section, however, may be guarded by a cover E which is provided with a downwardly projecting rib E¹ and is adapted to lie upon the ledge D² beneath the sliding door C¹. The 85 outer edge is strengthened by the rib E².

The opening D¹ is normally covered. When the lower section is to be filled, the door C¹ can be raised and the cover E can be removed. To facilitate the filling of the lower 90 section under such circumstances, we provide a chute which consists of the outwardly projecting bottom portion F with the sides F¹ and F². The bottom is provided with the opening F³ to register with the opening D¹ 95 when the cover is removed. It has a hook F⁶ to take under the edge of the bottom and a projection F⁴ to engage the same.

The devices shown in Figs. 1 to 7 are intended to illustrate separate sections which 100 are set up together and superimposed one on the other so as to form a case or cabinet of a series of sections. In the device of Fig. 7 the structure is modified by the suppression of certain parts and the insertion of the door G 105 having the knob G¹ and hinged at G² on the sides of the section.

The structures shown in Figs. 8 and 9 are intended to represent a complete case or cabinet 110 in which the several sections are perma-

nently united with each other. It is also intended to illustrate certain modifications which could be applied to the other form of structure. J is the back; J¹ the sides of a cabinet which is also provided with an intermediate vertical partition J², and preferably provided with the curved corner pieces J³. It is also provided with intermediate transverse portions J⁴. Thus a series of pigeonhole like compartments is produced in the cabinet. Each compartment preferably has in front a hinged door K with a glass front K¹. This door fits against a ledge K² on the partition J² and against a downwardly projecting closed portion A⁹, the lower end of which is received into the sockets A¹⁰. Beneath the hinged door is a pivoted closure consisting of the side portions M M and the cross piece M¹ with the curved projection M². The entire structure is pivoted at M³ so that when the structure is in the position shown in the lower part of Fig. 8, the part M¹ incloses the opening beneath the door and when it is in the position shown in the upper part of Fig. 8, the part M¹ serves as a platform leading into the compartment or section above. In this form of structure we prefer to fill from the rear and for that purpose each compartment has in its upper end a pivoted similar structure. The closure below the door is provided with the cross bar M⁴ which engages the pin M⁵ to limit the excursion of the structure. The filling opening closure consists of the side walls O having the cross piece O¹ and the closure or chute O², the whole pivoted at O³ in the opening O⁴. The chute O² is turned up at its outer end to form a strengthening rib O⁵. We have shown these several details of construction so as to present one practical form of our device, but it will be understood that these several structures can be greatly altered and some of the details may be omitted and one type substituted for another without departing from the spirit of our invention. We therefore wish to have our drawings taken diagrammatical rather than otherwise. Thus the glass B³ might be slidably supported by grooves impressed in the sides of the metal case to receive the edges of the glass or its support. A single compartment could be used separately.

The use and operation of our invention are as follows:—In grocery stores it is highly desirable to have means for storing considerable quantities of the various kinds of articles which are sold. For sanitary purposes they should be stored in sealed and closed compartments. For convenience the compartments should be such that the goods can be taken out while exposing the remaining material to the least possible degree. It is also of course highly desirable that the goods be exposed for advertising purposes or for inspection. The question of room is also serious where space in the large cities is

rented at such a high annual charge. A case of our sections or compartments set together or built up will occupy the least possible space, and can be set close to the walls if arranged to be filled from the front. When the sections are thus set together a suitable cover is put on the top case or compartment. The top compartment is filled from above and the others from the filling openings. The front is as far as possible of glass so that the interior and the material contained therein is open to inspection and observation. When the material is to be withdrawn in the case of structures shown in Figs. 1 to 6 the door is moved upwardly, whereupon by the usual scoop moved in over the filling opening cover and the bottom of the compartment, the material can be withdrawn from below. The only exposed material is that which forms the surface which indicates the angle of repose. The interior of the compartment is sealed by the material. If now the next lower compartment is to be filled it is only necessary to remove the cover of its filling opening, and place the filling chute in position as indicated in Fig. 2 whereupon it may be filled. Here again there is very little exposure of the interior of the compartment being filled. When it has been sufficiently filled the cover is restored to its position and the sliding door is moved down after the chute has been removed, and thus the compartments are again sealed. In Fig. 7 the action is the same except the hinged door is substituted for the sliding door, and the lower compartment can be filled without moving such door. In the structure shown in Fig. 8 the filling takes place at another point or at the back of the compartments.

We have mentioned some materials for which our invention is useful, but any kind of flowing solids may be used in our device.

We claim:—

1. A show case for flowing solids comprising a series of superimposed sections each bounded by inclosing approximately vertical walls and provided with a lower discharge opening leading laterally through one of such vertical walls, an upper movable closure for such opening, an inner guard for such opening to locate the lower edge of the face of the material when at its angle of repose inside of the vertical walls of the section, a filling opening in the upper part of each section located so as to fall between such movable closure and the guard when the sections are superimposed, a removable cover for such filling opening, said openings located so that the filling opening of one section is accessible from the discharge opening of the section above when the sections are assembled.

2. A show case for flowing solids comprising a series of superimposed sections each bounded by inclosing approximately vertical walls and combining with a discharge open-

ing an outer movable closure for such opening, an inner adjustable guard for such opening to locate the lower edge of the face of the material when at its angle of repose inside of the vertical walls of the section, a filling opening in the upper part of each section located so as to fall between such movable closure and the guard when the sections are superimposed, a removable cover for such filling opening, such opening so placed that the filling opening of one section is accessible from the discharge opening of the section above it when the sections are assembled.

3. A show case for flowing solids comprising a series of superimposed sections each bounded by inclosing approximately vertical walls and provided with a lower discharge opening, an outer vertically movable closure for such opening, an inner guard for such opening to locate the lower edge of the face of the material when at its angle of repose inside of the vertical walls of the section, a filling opening in the upper part of each section located so as to fall between such movable closure and the guard when the sections are superimposed, and a removable cover for such filling opening, the openings placed so that the filling opening of one section is accessible from the discharge opening of the section above when the two are assembled.

4. A show case for flowing solids comprising a series of superimposed sections each bounded by inclosing approximately vertical walls and provided with a lower discharge opening, an outer movable closure for such opening, an inner guard for such opening, a filling opening in the upper part of each section located so as to fall between such movable closure and the guard when the sections are superimposed, and a removable cover for such filling opening, the openings placed so that the filling opening of one section is accessible from the discharge opening of the section above when the two are assembled.

5. A show-case for flowing solids comprising a series of superimposed sections each bounded by inclosing approximately vertical walls and provided with a lower discharge

opening, an outer movable closure for such opening, an inner guard for such opening to locate the lower edge of the face of the material when at its angle of repose inside of the vertical walls of the section, and a filling opening in the upper part of each section, the openings placed so that the filling opening of one section is accessible from the discharge opening of the section above when the two are assembled.

6. A show case for flowing solids comprising a series of superimposed sections each bounded by inclosing approximately vertical walls, and provided with a lower discharge opening, an outer movable closure for such opening, an inner guard for such opening and a filling opening in the upper part of each section, the openings placed so that the filling opening of one section is accessible from the discharge opening of the section above when the two are assembled.

7. A show-case for flowing solids comprising a series of superimposed sections each bounded by inclosing approximately vertical walls and provided with a lower discharge opening, an outer vertically movable closure for such opening, an inner adjustable guard for such opening, and a filling opening in the upper part of each section, the openings placed so that the filling opening of one section is accessible from the discharge opening of the section above when the two are assembled.

8. A show-case for flowing solids comprising a series of superimposed sections each bounded by inclosing approximately vertical walls and each provided with a lower discharge opening at one side, a guard to prevent the material from freely flowing through such opening, a free opening between the inner end of such guard and the vertical walls, and a supply opening in the top of the lower section and beneath such free opening.
